Robert S. Wormser, Hillsdale, Mich., assignor to Game-Time, Inc., Litchfield, Mich., a corporation of Michigan

Filed Aug. 17, 1966, Ser. No. 3,496

Term of patent 14 years

(Cl. D34—15)

FIG. 1

FIG. 2

FIG. 1 is an elevational view of the right side of a duck-shaped seat for playground apparatus showing my new design, the left side being similar thereto,

FIG. 2 is a plan view of the novel design,

FIG. 3 is a front, elevational view of the design, and

FIG. 4 is a rear, elevational view.

The dominant features of my design reside in the full line portions shown with the broken lines omitted in FIGS. 3 and 4 for convenience of illustration.

I claim:

The ornamental design for duck-shaped seat for playground apparatus, substantially as shown and described.
